INDUCTOR COMPONENT

CROSS-REFERENCE TO RELATED APPLICATION

This application claims benefit of priority to U.S. Provisional Patent Application No. 63/079,901, filed Sep. 17, 2020, the entire content of which is incorporated herein by reference.

BACKGROUND

Technical Field

The present disclosure relates to an inductor component.

Background Art

JP-A-2013-98350 that is a Japanese patent application laid-open publication discloses a method of manufacturing a multi-layered inductor component having a multi-layer glass body that incorporates conductors inside. Specifically, prepared are a plurality of glass green sheets made from glass paste containing glass powder and thereafter printed and applied with conductor paste containing conductor powder such as Ag or Cu. The plurality of glass green sheets printed and applied with conductor paste are then layered and cut into individual pieces. At this time, ends of the conductor paste are exposed from each individual piece.

Next, these individual pieces are each fired to form a multi-layer glass body of the sintered glass paste and form inner conductors of the sintered conductor paste. At this time, the inner conductors are integrated with the multi-layer glass body and are incorporated inside the multi-layer glass body, with only the ends being exposed.

The ends of the inner conductors exposed from the multi-layer glass body are then plated to form terminal electrodes for electrical connection to the exterior. The multi-layered inductor component is thus completed that includes an inductor element composed of the inner conductors and the terminal electrodes.

SUMMARY

Different from the multi-layered inductor component above, a novel inductor component has been proposed in U.S. patent application Ser. No. 16/838,918 based on U.S. Provisional Patent Application No. 62/830,158.

This inductor component comprises a single-layer glass plate; outer-surface conductors as at least a part of an electric element, disposed above an outer surface of the single-layer glass plate; and terminal electrodes as terminals of the electric element, disposed above the outer surface of the single-layer glass plate and electrically connected to the outer-surface conductors.

This inductor component further comprises through wirings, as at least a part of the electric element, extending through through holes formed in the single-layer glass plate and electrically connected to the outer-surface conductors.

In this inductor component, the outer surface includes a bottom surface as one of principal surfaces of the single-layer glass plate, and a top surface positioned on a back side of the bottom surface; and the terminal electrodes include a first terminal electrode and a second terminal electrode that are input/output terminals of the electric element. The first terminal electrode and the second terminal electrode are shaped to have, above the bottom surface, principal surfaces

2

parallel to the bottom surface. The outer-surface conductors include bottom-surface conductors and top-surface conductors that are disposed above the bottom surface and above the top surface, respectively, and that are connected to each other via the through wirings. Also, a circularly extending wiring composed of the bottom-surface conductors, the top-surface conductors, and the through wirings circularly extends around a winding axis parallel to the bottom surface.

For standardization, the inductor component often has an outer shape allowing, on a mounting board, a rectangular, for example, quadrangular arrangement with the length doubling the width. That is, in the inductor component above, the single-layer glass plate may be of a rectangular parallelepiped shape having a length, a width, and a height, the length being longer than the width, with one principal surface defined by the length and the width acting as the bottom surface. In this case, the following problems occur.

FIG. 3 is a schematic perspective view showing an inductor component 1 of Comparative Example. Disposed in the same layer of the inductor component 1 are a first terminal electrode 121 and a second terminal electrode 122 and bottom-surface conductors 11b of a circularly extending wiring 110, which are disposed above a bottom surface 100b. In this case, the manufacturing is easy since the first terminal electrode 121, the second terminal electrode 122, and the bottom-surface conductors 11b can be formed at the same time. On the contrary, in the inductor component 1, the formation range of the bottom-surface conductors 11b is limited by the first terminal electrode 121 and the second terminal electrode 122, limiting the number of circulations of the circularly extending wiring 110.

FIG. 4 is a schematic perspective view showing an inductor component 1a of Comparative Example. In the inductor component 1a, the bottom-surface conductors 11b extend on the bottom surface 100b in the length direction (X direction) of a single-layer glass plate 10, with an underlying insulation layer 15 being disposed on the bottom-surface conductors 11b, terminal electrodes 12 being disposed on the underlying insulation layer 15. In this case, since the outer-surface conductors 11 and the terminal electrodes 12 are formed in different layers, the outer-surface conductors 11 and the terminal electrodes 12 can be designed with greater freedom in layout. Furthermore, since the inner diameter of the circularly extending wiring is increased by forming the outer-surface conductors 11 along the length direction of the single-layer glass plate 10, the acquisition efficiency of an L value and a Q value of the inductor element on the outer shape of the inductor component 1a are improved. On the other hand, since in the inductor component 1a the winding axis of the circularly extending wiring becomes parallel to the width direction of the single-layer glass plate 10, the winding axis becomes relatively short, limiting the number of circulations of the circularly extending wiring. Moreover, the inductor component 1a undergoes a large change in the inductance value (L value) per number of circulations of the circularly extending wiring, rendering fine adjustment of the L value difficult.

An inductor component according to an aspect of the present disclosure has a structure in which the number of circulations of a circularly extending wiring is less limited while reducing the influence of firing. Furthermore, the inductor component according to an aspect of the present disclosure relatively reduces the change in L value per the number of circulations of the circularly extending wiring, facilitating fine adjustment of L value.

An inductor component according to an aspect of the present disclosure comprises a single-layer glass plate of a

rectangular parallelepiped shape with a length, a width, and a height, the length being longer than the width, the single-layer glass plate having a bottom surface defined by the length and the width and a top surface positioned on a back side of the bottom surface; bottom-surface conductors and top-surface conductors disposed above the bottom surface and above the top surface, respectively; through wirings each extending through a corresponding one of through holes formed in the single-layer glass plate; an underlying insulation layer disposed above the bottom-surface conductors; and a first terminal electrode and a second terminal electrode disposed above the underlying insulation layer. The bottom-surface conductors, the top-surface conductors, and the through wirings are electrically connected to each other to constitute a circularly extending wiring that circularly extends around a winding axis parallel to the bottom surface and the length. The circularly extending wiring, the first terminal electrode, and the second terminal electrode are electrically connected to each other to constitute an inductor element.

In this specification, "single-layer glass plate" is a concept against the multi-layer glass body and, more specifically, refers to a glass plate not incorporating the conductors integrated inside the glass, that is, the inner conductors.

"Outer surface of the single-layer glass plate" including the bottom surface and the top surface of the single-layer glass plate does not simply mean a surface of the single-layer glass plate facing its outer peripheral side, but means a surface as a boundary between the outer side and the inner side of the single-layer glass plate. "Above the outer surface (bottom surface and top surface)" does not refer to an absolute unidirectional direction, such as vertically above, which is defined by the direction of gravity, but refers to a direction, with respect to the outer surface, going toward the outer side, of the outer side and the inner side when the outer surface is the boundary therebetween. Therefore, "above the outer surface" is a relative direction defined by the orientation of the outer surface. From the above, "disposed above the outer surface of the single-layer glass plate" means being positioned on the outer side of the glass body and not being incorporated inside the glass body of the single-layer glass plate.

"Outer surface of the single-layer glass plate" above includes also the surfaces of the through wirings and of the grooved portions since they are surfaces becoming the boundary between the outer side and the inner side of the glass body. The boundary above between the outer side and the inner side of the glass body can easily be grasped by cross-section analysis of the single-layer glass plate using, for example, a scanning electron microscope (SEM).

"Above" with respect to an element includes not only "above" spaced apart from the element, that is, an upper position via another object on the element or a spaced-apart upper position, but also a directly-above position in contact with (i.e. on) the element.

In the inductor component of the aspect above, the bottom-surface conductors, the top-surface conductors, and the through wirings are not incorporated inside the single-layer glass plate, reducing the influence caused by the firing. In the inductor component of the aspect above, the first terminal electrode and the second terminal electrode are disposed above the underlying insulation layer disposed above the bottom-surface conductors, reducing the limitation in the number of circulations of the circularly extending wiring. In the inductor component of the aspect above, the circularly extending wiring circularly extends around the winding axis parallel to the length of the single-layer glass

plate, thus reducing the limitation in the number of circulations of the circularly extending wiring and relatively reducing the change in the L value per the number of circulations of the circularly extending wiring, to consequently facilitate the fine adjustment of the L value.

BRIEF DESCRIPTION OF THE DRAWINGS

FIG. 1 is a schematic perspective view of an inductor component as viewed from its top surface side;

FIG. 2 is a schematic top view of the inductor component as viewed from its top surface side;

FIG. 3 is a schematic perspective view of an inductor component as viewed from its bottom surface side;

FIG. 4 is a schematic perspective view of an inductor component as viewed from its bottom surface side;

DETAILED DESCRIPTION

An embodiment as one mode of the present disclosure will now be described with reference to the drawings. Note that the drawings are schematic ones and that the dimensions, positional relationships, and shapes of the whole and parts may be modified or omitted.

Embodiment

An inductor component 6 according to the embodiment will be described below. FIG. 1 is a schematic perspective view of the inductor component 6 as viewed from its top surface side. FIG. 2 is a schematic top view of the inductor component 6 as viewed from its top surface side.

1. Overview Structure

An overview structure of the inductor component **6** will be described. The inductor component **6** is a surface-mount-type electronic component including an inductor element **L** used as an electric element in e.g. a high-frequency signal transmission circuit. The inductor component **6** comprises: a single-layer glass plate **60** of a rectangular parallelepiped shape with a length **Le**, a width **W**, and a height **T**, the length **Le** being longer than the width **W**, the single-layer glass plate **60** having a bottom surface **600b** defined by the length **Le** and the width **W** and a top surface **600t** positioned on the back side of the bottom surface **600b**; bottom-surface conductors **61b** and top-surface conductors **61t** that are disposed above the bottom surface **600b** and above the top surface **600t**, respectively; through wirings **63** extending through through holes **V** formed in the single-layer glass plate **60**; an underlying insulation layer **65** disposed above the bottom-surface conductors **61b**; and a first terminal electrode **621** and a second terminal electrode **622** as terminal electrodes **62** disposed above the underlying insulation layer **65**.

In the inductor component **6**, a circularly extending wiring **610** formed from the bottom-surface conductors **61b**, the top-surface conductors **61t**, and the through wirings **63** that are electrically connected together circularly extends around a winding axis **AX** parallel to the bottom surface **600b** and the length **Le** so that the circularly extending wiring **610**, the first terminal electrode **621** and the second terminal electrode **622** are electrically connected together to constitute the inductor element **L**.

Due to the structure above, in the inductor component **6**, since the bottom-surface conductors **61b** and the top-surface conductors **61t** as the outer-surface conductors **61** and the terminal electrodes **62** are disposed above the bottom surface **600b** and the top surface **600t** as the outer surfaces **600** of the single-layer glass plate **60**, the outer-surface conductors **61** and the terminal electrodes **62** are not incorporated into the single-layer glass plate **60**. Similarly, in the inductor component **6**, the through wirings **63** extend through the through holes **V** as the outer surfaces **600** of the single-layer glass plate **60** so that the through wirings **63** are also not incorporated into the single-layer glass plate **60**. Accordingly, the inductor component **6** can reduce the influence of firing.

Further, in the inductor component **6**, since the first terminal electrode **621** and the second terminal electrode **622** are disposed above the underlying insulation layer **65** disposed above the bottom-surface conductors **61b**, it is possible to set the formation range of the bottom-surface conductors **61b**, independently of the first terminal electrode **621** and the second terminal electrode **622**, resulting in improved design freedom of the circularly extending wiring **610** and in less limitation to the number of circulations of the circularly extending wiring **610**.

Further, in the inductor component **6**, since the circularly extending wiring **610** circularly extends around the winding axis **AX** parallel to the length **Le** of the single-layer glass plate **60**, the winding axis **AX** becomes relatively long, resulting in improved design freedom of the circularly extending wiring **610** and in less limitation to the number of circulations of the circularly extending wiring **610**. Furthermore, in this case, since the inner diameter of the circularly extending wiring **610** is oriented to a direction parallel to the width **W** of the single-layer glass plate **60**, the inner diameter can become relatively small, resulting in a relatively small change of the **L** value per number of circulations of the circularly extending wiring **610**. For this reason, the inductor component **6** allows easy fine adjustment of the **L** value. In

particular, this is advantageous for the inductor component **6** when narrowing the characteristic deviation is required in circuit designing.

Further, in the inductor component **6**, the first terminal electrode **621** and the second terminal electrode **622** are shaped to have, above the bottom surface **600b**, principal surfaces parallel to the bottom surface **600b**. Due to the structure above, since the inductor component **6** comprises, on the bottom surface **600b** side, the input/output terminals of the inductor element **L** having a surface allowing adhesion of the solder in the direction parallel to the bottom surface **600b**, it becomes a surface-mount-type electronic component enabling surface mounting on the bottom surface **600b** as a mounting surface, with a reduced mounting area.

Note that the first terminal electrode **621** and the second terminal electrode **622** are shaped to have principal surfaces parallel to the bottom surface **600b** but that they may include other portions than the above. For example, the first terminal electrode **621** and the second terminal electrode **622** may also be of an L shape having a principal surface also above an end surface vertical to the bottom surface **600b** of the single-layer glass plate **60** and, furthermore, they may also be of a slant electrode shape having triangular principal surfaces also above side surfaces vertical to the bottom surface **600b** and the end surface of the single-layer glass plate **60**. Then, the first terminal electrode **621** and the second terminal electrode **622** may also have a principal surface also above the top surface **600t** of the single-layer glass plate **60**, or they may also be of a five-surface electrode shape having principal surfaces above the bottom surface **600b**, the top surface **600t**, the terminal end, and two side surfaces.

Further, in the inductor component **6**, the first terminal electrode **621** and the second terminal electrode **622** lie at positions overlapping with the bottom-surface conductors **61b** as viewed from a direction parallel to the height **T**. This allows the bottom-surface conductors **61b** to be formed in a wider range, enabling improvement in design freedom of the circularly extending wiring **610** and increase in the **L** value.

Further, in the inductor component **6**, the circularly extending wiring **610** circulates twice at each of a position overlapping with the first terminal electrode **621** and a position overlapping with the second terminal electrode **622**, as viewed from the direction parallel to the height **T**. This can further increase the **L** value. Note in the inductor component **6** that at the position overlapping with the first terminal electrode **621** or at the position overlapping with the second terminal electrode **622** as viewed from the direction parallel to the height **T**, the circularly extending wiring **610** may not circulate, may circulate once, or may circulate three or more times.

However, when the overlap increases between the bottom-surface conductors **61b** and the first terminal electrode **621** or the second terminal electrode **622**, the **Q** value of the inductor element **L** tends to decrease due to formation of the stray capacitance. From this respect, it is more preferable that at each of the position overlapping with the first terminal electrode **621** and the position overlapping with the second terminal electrode **622** as viewed from the direction parallel to the height **T**, the circularly extending wiring **610** do not circulate three or more times.

It is also preferable that the underlying insulation layer **65** cover the entire bottom surface **600b**. This prevents the bottom surface **600b** from directly interfering with the exterior, resulting in improved strength and durability of the single-layer glass plate **60**.

It is also preferable that the entire bottom-surface conductors **61b** be covered with the underlying insulation layer **65**. This can suppress short circuits between the bottom-surface conductors **61b** and between the bottom-surface conductors **61b** and the terminal electrodes **62**. Further, due to no direct interference of the bottom-surface conductors **61b** with the exterior, damage to the bottom-surface conductors **61b** and short circuits with external circuits can be prevented.

Further, in the inductor component **6**, by comprising the through wirings **63**, the wiring can be formed in the vertical direction with respect to the outer-surface conductors **61** and the terminal electrodes **62** disposed above the outer surfaces **600**, improving the formation freedom of the inductor element **L**.

Further, in the inductor component **6**, since the circularly extending wiring **610** circularly extends around the winding axis **AX** parallel to the bottom surface **600b**, the winding axis **AX** becomes parallel to the mounting surface of the inductor component **6**, with the result that magnetic flux passing through the inner diameter of the circularly extending wiring **610** as a main component of magnetic flux generated by the inductor element **L** does not intersect the mounting board, making it possible to reduce lowering of the **Q** value of the inductor element **L** caused by the eddy current loss and to reduce noise radiation onto the mounting board.

Hereinafter, for convenience of description, as shown in the drawings, let **X** direction be a direction extending parallel to the length **Le** of the single-layer glass plate **60** and toward the second terminal electrode **622** from the first terminal electrode **621**. Further, of directions orthogonal to **X** direction, let **Z** direction be a direction extending parallel to the height **T** of the single-layer glass plate **60** and toward the top surface **600t** from the bottom surface **600b**, while let **Y** direction be a direction extending parallel to the width **W** of the single-layer glass plate **60**, i.e. orthogonal to **X** direction and **Z** direction and constituting a right-handed system when arranged in the order of **X**, **T**, and **Z**. Further, when the orientations are not considered, etc., directions parallel to **X** direction, **Y** direction, and **Z** direction, respectively, may be referred to as **L** direction, **W** direction, and **T** direction, respectively.

From the definitions above, above the bottom surface **600b**, which is an outer surface **600**, refers to a direction that goes opposite to the **z** direction from the bottom surface **600b**; and above the top surface **600t**, which is an outer surface **600**, refers to a direction that goes towards the **z** direction from the top surface **600t**. The thickness of each outer-surface conductor **61** is a thickness in a direction that is orthogonal to the outer surface **600** that is positioned below the outer-surface conductors **61**.

2. Structure of Each Portion

Single-Layer Glass Plate **60**

The single-layer glass plate **60** functions as an insulator and a structural body of the inductor component **6**. From the viewpoint of manufacturing methods, it is desirable that the single-layer glass plate **60** be made of a photosensitive glass plate, a typical example thereof being Foturan II (registered trademark of Schott AG). In particular, it is desirable that the single-layer glass plate **60** contain cerium oxide (ceria: CeO_2), in which case the cerium oxide becomes a sensitizing agent, and processing by photolithography is further facilitated.

However, the single-layer glass plate **60** can be processed by, for example, machining, such as drilling or sandblasting; dry/wet etching using, for example, a photoresist/metal

mask; or laser processing. Therefore, a glass plate that is not photosensitive may be used. The single-layer glass plate **60** may be one in which glass paste has been sintered, or may be formed by a publicly known method, such as a float method.

The single-layer glass plate **60** is a single-layer plate member in which wirings, such as internal conductors integrated with the inside of a glass body, are not placed in the glass body. In particular, the single-layer glass plate **60** includes the outer surfaces **600** as the boundaries between the outer side portion and the inner side portion of the glass body. Since the through holes **V** formed in the single-layer glass plate **60** are also boundaries between the outer side portion and the inner side portion of the glass body, they are defined as the outer surfaces **600**. Although the single-layer glass plate **60** is basically in an amorphous state, the single-layer glass plate **60** may include the crystallization portion. For example, when Foturan II above is used, although the dielectric constant of amorphous glass is 6.4, the dielectric constant can be reduced to 5.8 by crystallization. Therefore, it is possible to reduce the stray capacitance between conductors near the crystallization portion.

Outer-Surface Conductors **61**

The outer-surface conductors **61** are wirings disposed above the corresponding one of the outer surfaces **600** of the single-layer glass plate **60**, that is, on the outer side portion of the single-layer glass plate **60**, and constitute at least part of the inductor element **L**, which is an electrical element. More specifically, the outer-surface conductors **61** include the bottom-surface conductors **61b** that are disposed on the bottom surface **600b** of the single-layer glass plate **60** and the top-surface conductors **61t** that are disposed on the top surface **600t** of the single-layer glass plate **60**. Each bottom-surface conductor **61b** and each top-surface conductor **61t** extend in the **W** direction while being slightly tilted in the **L** direction. Therefore, the circularly extending wiring **610** has a substantially helical shape in which a change-over to a next spiral occurs at each bottom-surface conductor **61b** and at each top-surface conductor **61t**.

The outer-surface conductors **61** are made of conductive materials having high conductivity, such as copper, silver, gold, or an alloy thereof. The outer-surface conductors **61** may be metal films formed by, for example, plating, evaporation, or sputtering, or may be a metal sintered body in which a conductor paste has been applied and sintered. The outer-surface conductors **61** may have a multi-layer structure including a plurality of metal layers that are stacked upon each other, or may be one in which, for example, when a underlying insulation layer **65** is not included, a film made of nickel, tin, gold, or the like is formed at an outermost layer. It is desirable that the thickness of the outer-surface conductors **61** be 5 μm or more and 50 μm or less (i.e., from 5 μm to 50 μm).

It is desirable that the outer-surface conductors **61** be formed by a semi-additive method. This makes it possible to form the outer-surface conductors **61** having low electrical resistance, high precision, and high aspect. For example, the outer-surface conductors **61** can be formed as follows. First, a titanium layer and a copper layer are formed in this order by performing a sputtering method or electroless plating on the entire outer surfaces **600** of each single-layer glass plate **60** after division into individual pieces to form a seed layer, and a patterned photoresist is formed on the seed layer. Next, a copper layer is formed by electroplating on the seed layer at a cavity portion of the photoresist. Thereafter, the photoresist and the seed layer are removed by wet etching or dry etching. Therefore, the outer-surface conductors **61** that

have been patterned to any shape can be formed on the outer surfaces **600** of each single-layer glass plate **60**.

Terminal Electrodes **62**

The terminal electrodes **62** are terminals of the inductor element **L** and are disposed above the outer surface **600** of the single-layer glass plates **60** and are electrically connected to the outer-surface conductors **61**. As shown in FIG. 1, the terminal electrodes **62** are exposed to the outside of the inductor component **6**. More specifically, the terminal electrodes **62** include the first terminal electrode **621** and the second terminal electrode **622** that are disposed on the bottom surface **600b** of the single-layer glass plate **60**, and the first terminal electrode **621** and the second terminal electrode **622** are exposed to the outside only at the bottom surface **600b**.

However, the terminal electrodes **62** are not limited to the structure above. The number of terminal electrodes **62** may be three or more, and the terminal electrodes **62** may also be formed on a side surface adjacent to the bottom surface **600b**, or on the top surface **600t**. The terminal electrodes **62** can be formed by using any of the materials and manufacturing methods exemplified for the outer-surface conductors **61**.

The terminal electrodes **62** need not protrude from the underlying insulation layer **65** covering the bottom-surface conductors **61b**. A principal surface of each terminal electrode **62** may be positioned closer than the underlying insulation layer **65** to a side of the single-layer glass plate **60**. In this case, mountability may be increased by forming a solder ball on the principal surface of each terminal electrode **62**.

Through Wirings **63**

The through wirings **63** are wirings that extend through the corresponding through holes **V** formed in the single-layer glass plate **60** and that are electrically connected to the corresponding outer-surface conductors **61**, and constitute at least part of the inductor element **L**. In particular, the circularly extending wiring **610** including the outer-surface conductors **61** and the through wirings **63** has a substantially helical shape circularly extending around the winding axis **AX** and constitutes the main portion of the inductor element **L**. The through wirings **63** can be formed in the through holes **V** previously formed in the single-layer glass plate **60** by using any of the materials and manufacturing methods exemplified for the outer-surface conductors **61**.

Underlying Insulation Layer **65**

The underlying insulation layer **65** is a member that has the role of preventing damage to the outer-surface conductors **61** from occurring by protecting the outer-surface conductors **61** from external forces, and the role of increasing the insulation property of the outer-surface conductors **61**. It is desirable that the underlying insulation layer **65** be, for example, an inorganic film made of an oxide, a nitride, or an oxynitride of, for example, silicon or hafnium, having excellent insulation property and capable of being easily thinned. However, the underlying insulation layer **65** may be a resin film made of, for example, epoxy or polyimide that allows easier formation thereof. In particular, it is desirable that the underlying insulation layer **65** be made of a low dielectric constant material, whereby the stray capacitance formed between the bottom-surface conductors **61b** and the terminal electrodes **62** can be reduced.

As shown in FIGS. 1 and 2, the underlying insulation layer **65** may cover the single-layer glass plate **60** and the top-surface conductors **61t** on the top surface **600t**. This

makes it possible to form a pickup surface of a mounting device when mounting the inductor component **6** onto the mounting board.

By using the underlying insulation layer **61**, it is possible to adjust, for example, the heights of formation and the degree of close contact of the outer-surface conductors **61** and the terminal electrodes **62**, and the electrical characteristics of the inductor element **L**.

The underlying insulation layer **65** can be formed by, for example, laminating with a resin film, such as ABF GX-92 (manufactured by Ajinomoto Fine-Techno Co., Inc.), or applying, subjecting to thermosetting, etc. a paste-like resin.

In the inductor component **6**, the underlying insulation layer **65** is disposed on the bottom-surface conductors **61b**, and the terminal electrodes **62** are disposed on the underlying insulation layer **65**. In this way, by forming the outer-surface conductors **61** and the terminal electrodes **62** in different layers, it is possible to design a layout of the outer-surface conductors **61** and the terminal electrodes **62** with greater freedom.

Via through wirings formed in the underlying insulation layer **65**, the terminal electrodes **62** can be electrically connected to the bottom-surface conductors **61b** and the through wirings **63**. Instead of disposing only the terminal electrodes **62** on the underlying insulation layer **65**, as a re-wiring layer, a wiring that is electrically connected to the bottom-surface conductors **61b** and the through wirings **63** may be disposed at the underlying insulation layer **65**. This allows the inductor element **L** to be designed with greater freedom.

3. Processing Method of Single-Layer Glass Plate **60**

In the inductor component **6**, the single-layer glass plate **60** is a processed body including previously formed through holes **V**, etc., prior to forming the inductor element **L** including, for example, the outer-surface conductors **61**, the terminal electrodes **62**, and the through wirings **63**. In processing the single-layer glass plate **60**, although it is possible to use publicly known methods including the above-described methods, it is most desirable to perform the processing using photosensitive glass, thereby allowing the processing to be performed with high precision. The processing method using photosensitive glass is described below.

(1) Preparation of Board

First, a photosensitive glass board, which is an assembly of portions that become the single-layer glass plates **60**, is prepared. For the photosensitive glass board, for example, Foturan II can be used. In general, the photosensitive glass board contains an oxide of silicon, lithium, aluminum, cerium, or the like to allow photolithography with high precision.

(2) Exposure

Next, portions of the prepared photosensitive glass board where, for example, the through holes, the cavities, the crystallization portion, and the grooved portions are to be formed are irradiated with, for example, ultraviolet light having a wavelength of approximately 310 nm. The irradiation with ultraviolet light causes, for example, metal ions, such as cerium ions, in the photosensitive glass to be oxidized by light energy to discharge electrons. Here, the final processing depth of the single-layer glass plates **60** can be controlled by adjusting the irradiation amount of ultraviolet light in accordance with the thickness of the photosensitive glass board. For example, by setting the irradiation amount to a large amount, it is possible to form the through holes **V** that extend up to the top surface **600t** from the bottom surface **600b** of each single-layer glass plate **60**,

11

whereas, by adjusting the irradiation amount to a small amount, it is possible to form the non-through holes, such as the cavities and the grooved portions.

As an exposure device used in irradiating the photosensitive glass board with ultraviolet light, a contact aligner or a stepper that allows ultraviolet light having a wavelength of approximately 310 nm to be obtained can be used. Alternatively, a laser irradiation device including a femtosecond laser can be used as a light source. When a femtosecond laser is used, by condensing laser light in an internal portion of the photosensitive glass board, it is possible to discharge electrons from metal oxide only at a light-condensing portion. That is, it is possible to photosensitize only the internal portion without photosensitizing a surface of a laser-light irradiation portion of the photosensitive glass board.

Therefore, each single-layer glass plate 60 is designed with greater freedom. For example, processing becomes possible for inner portions that are not exposed at the bottom surface 600b and the top surface 600t, which are surfaces where the outer-surface conductors 61 of the inductor component 6 are formed, that is, for portions of the photosensitive glass board other than the exposed surfaces.

(3) Firing

The photosensitive glass board after the exposure above is fired. Specifically, the photosensitive glass board is fired at temperatures in two stages, for example, first, at a temperature near 500° C. Therefore, in the ultraviolet-light irradiation portion of the photosensitive glass board, ions, such as silver ions, gold ions, or copper ions, are reduced by discharged electrons to form a nano-cluster of metal atoms. Next, the photosensitive glass board is fired at a temperature near 560° C. Therefore, the nano-cluster of metal atoms becomes a crystalline nucleus and a crystal phase of, for example, lithium metasilicate is deposited in the vicinity of the crystalline nucleus. The crystal phase of, for example, lithium metasilicate easily dissolves in hydrofluoric acid, and this characteristic is used in the next etching step.

In uniformly depositing the crystal phase above in a plane of the photosensitive glass board, the temperature distribution inside a firing furnace needs to be uniform and is desirably within $\pm 3^\circ$ C.

(4) Etching

After the firing, the etching step using a hydrofluoric acid aqueous solution is performed. It is desirable that the concentration of hydrofluoric acid aqueous solution be, for example, 5 to 10%. In the etching step, the entire photosensitive glass board after the firing above is immersed in the hydrofluoric acid aqueous solution. Therefore, only the crystal phase inside the board is etched and the through holes or the non-through holes are formed. For the purpose of smoothening the surface of the etched photosensitive glass board, the hydrofluoric acid aqueous solution may contain an acid other than hydrofluoric acid, such as hydrochloric acid or nitric acid.

When the crystallization portion is to be formed in each single-layer glass plate 60, for example, a portion of the crystal phase that becomes the crystallization portion may be covered with a barrier layer that is resistant to a hydrofluoric acid aqueous solution to prevent the hydrofluoric acid aqueous solution from being immersed in the crystal phase. After the step above, if necessary, the thickness of the photosensitive glass board may be adjusted by grinding the photosensitive glass board.

(5) Formation of Conductors

The outer-surface conductors 61, the through wirings 63, etc., are formed at the corresponding outer surfaces of the photosensitive glass board after the etching step above by,

12

for example, a semi-additive method. The outer-surface conductors 6 and the through wirings 63 may be formed from a single seed layer, or may be formed by separate steps. When the respective thicknesses of the outer-surface conductors 61 are to be different, for example, while covering a part of each outer-surface conductor 61 with the protective film 14, only exposed portions of each outer-surface conductor 61 may be further subjected to electroplating, or a seed layer may be formed again to form a multi-layered conductor layer.

After forming the conductors, the conductors are coated or laminated with a resin to form the underlying insulation layer 65, and the terminal electrodes 62 are formed on the underlying insulation layer 65 by the same method as described above. Afterward, the photosensitive glass board is divided into individual pieces by, for example, using a dicing blade, so that an inductor component 6 including the single-layer glass plate 60 is completed.

In the manufacturing method above, since after sintering each single-layer glass plate 60 of the inductor component 6, the conductors, such as the outer-surface conductors 61, the terminal electrodes 62, and the through wirings 63 are formed, it is possible to reduce the influence caused by the firing.

In the above, although, in the etching step, the crystallization portion is formed by covering a portion of the crystal phase with a barrier layer that is resistant to a hydrofluoric acid aqueous solution, it is not limited thereto. For example, it is possible to, by irradiating with ultraviolet light again the photosensitive glass board after the formation of conductors or the inductor component 6 after the division into pieces, slightly crystallize the irradiation portion and form the crystallization portion. This causes the crystallization portion to be formed with greater freedom.

4. Modifications

Although, as the embodiment, the inductor component 6 has been described, the inductor component 6 may have additional structures below that have not been described above. For example, in the inductor component 6, the single-layer glass plate 60 may include a reinforcing portion that is harder than the vicinity thereof. An electronic component, such as the inductor component 6, tends to be damaged due to an external force or a thermal shock applied to the inductor component 6 during a manufacturing process or after mounting. In particular, at interfaces between elements having different physical properties, that is, between the single-layer glass plate 60, the outer-surface conductors 61, the terminal electrodes 62, and the through wirings 63, stress tends to concentrate and cracks tend to be produced in the single-layer glass plate 60 with the interfaces as starting points. In the structure above, since the strength can be properly reinforced by the reinforcing portion against local damages and cracks, the strength of the inductor component 6 is increased.

The reinforcing portion can be formed, for example, by using a photosensitive glass for the single-layer glass plate 60 and, similarly to the crystallization portion above, by partly crystallizing the single-layer glass plate 60. The transmittance of the reinforcing portion can be controlled as appropriate on the basis of, for example, the irradiation amount/irradiation time of ultraviolet light or heating.

In particular, it is desirable that the reinforcing portion be positioned below the outer-surface conductors 61 or below the terminal electrodes 62. This makes it possible to effectively reduce the local damages and cracks above. Further, it is more desirable that the reinforcing portion be positioned

13

below an outer peripheral edge of each outer-surface conductor **61** or below an outer peripheral edge of each terminal electrode **62**.

Although in the inductor component **6**, the outer-surface conductors **61** have been a part of the inductor element **L**, the outer-surface conductors **61** are not limited thereto. The outer-surface conductors **61** may be a part of electric elements other than the inductor element **L**. For example, the outer-surface conductors **61** may be a part of a capacitor element. In this case, the inductor component becomes an LC composite filter component including also the capacitor element.

Similarly, the inductor component **6** may include a plurality of electric elements. For example, the inductor component **6** may include two or more inductor elements, two more capacitor elements, or a combination thereof.

The manufacturing method of the inductor component **6** can also be changed as appropriate. For example, in the manufacturing method described above, individual pieces of single-layer glass plates may be formed by cutting the photosensitive glass board by a photolithography method, the photosensitive glass board having the outer-surface conductors formed thereon.

According to the manufacturing method above, it is possible to cut the photosensitive glass board with high precision while reducing chipping when dividing the photosensitive glass board into pieces. Since this method does not cause a physical shock to be applied to the photosensitive glass board at the time of dicing unlike when a dicing blade is used, it is possible to suppress micro-cracks from being produced in the single-layer glass plates. Further, compared to when a dicing blade is used, it is possible to reduce a cutting margin when dividing the photosensitive glass board into pieces, and to increase the number of single-layer glass plates that can be obtained from a photosensitive glass board of the same size.

Although the inductor component **6** has included one single-layer glass plate **60**, the structure may be such that a plurality of single-layer glass plates are joined and stacked together. An example of a method of joining the single-layer glass plates to each other includes using a photosensitive glass for the single-layer glass plate and activating the surface of the photosensitive glass by wet etching or dry etching, whereby the glass plates can be directly joined to each other. The single-layer glass plates may be joined to each other by interposing an adhesive layer, such as a thermosetting resin layer or a thermoplastic resin layer, between the top surface of a single-layer glass plate and the bottom surface of another single-layer glass plate.

At this time, for example, the outer-surface conductors may be formed on a single-layer glass plate before the joining or may be formed on single-layer glass plates joined together. Without being limited thereto, grooved portions may be formed on the top surface of the joined single-layer glass plates or single-layer glass plates may be joined together after formation of the grooved portions on the top surface, after which the outer-surface conductors may be formed in the grooved portions. By forming the outer-surface conductors in the grooved portions after joining the single-layer glass plates, two single-layer glass plates can come into more intimate contact with each other, which is desirable. Even if an adhesive layer is used, spaces between the single-layer glass plates can be filled due to plastic deformation of the adhesive layer, which is desirable.

Although the inductor component **6** has been a surface-mount-type electronic component, this is not limitative. For

14

example, the inductor component **6** may be a three-dimensional mounting electronic component.

The various features described above can be individually added, deleted, and changed. Further, publicly known structures can be added to, deleted from, and changed from these modes.

The present disclosure is not limited to the embodiment described above and may be changed in design without departing from the spirit of the present disclosure. For example, respective feature points of the reference examples described below may variously be incorporated in the present disclosure.

FIRST REFERENCE EXAMPLE

An inductor component **1** according to a first reference example is described below. FIG. 3 is a schematic perspective view of the inductor component **1** as viewed from a bottom surface. FIG. 5 is a schematic perspective view of the inductor component **1** as viewed from a top surface.

1. General Structure

A general structure of the inductor component **1** is described. The inductor component **1** is a surface-mount-type electronic component that includes, as an electrical element, for example, an inductor element **L** used in a high-frequency signal transmission circuit. The inductor component **1** includes a single-layer glass plate **10**, outer-surface conductors **11** that are each disposed above a corresponding one of outer surfaces **100** of the single-layer glass plate **10** and that are at least part of the inductor element **L**, and terminal electrodes **12** that are terminals of the inductor element **L**, the terminal electrodes **12** being disposed above a bottom surface **100b** of the single-layer glass plate **10** and being electrically connected to the outer-surface conductors **11**.

Due to the structure above, since, in the inductor component **1**, the outer-surface conductors **11** and the terminal electrodes **12** are disposed above the corresponding outer surfaces **100** of the single-layer glass plate **10**, the outer-surface conductors **11** and the terminal electrodes **12** are not placed in the single-layer glass plate **10**. Therefore, the inductor component **1** makes it possible to reduce the influence of firing.

The inductor component **1** further includes through wirings **13** that are at least part of the inductor element **L**, the through wirings **13** extending through holes **V** formed in the single-layer glass plate **10** and being electrically connected to the outer-surface conductors **11**.

Due to the structure above, in the inductor component **1**, it is possible to form wirings in a vertical direction with respect to the outer-surface conductors **11** and the terminal electrodes **12**, which are disposed above the corresponding outer surfaces **100**, and the inductor element **L** is formed with greater freedom.

In the inductor component **1**, the outer surfaces **100** of the single-layer glass plate **10** include the bottom surface **100b** that is one principal surface of the single-layer glass plate **10**, and the terminal electrodes **12** include a first terminal electrode **121** and a second terminal electrode **122**, which are input/output terminals of the inductor element **L**. Further, in the inductor component **1**, at locations above the bottom surface **100b**, the first terminal electrode **121** and the second terminal electrode **122** each have a shape including a principal surface that is parallel to the bottom surface **100b**.

Due to the structure above, since the inductor component **1** includes the input/output terminals of the inductor element **L**, each having a surface that allows solder to adhere in a

direction parallel to the bottom surface **100b**, on a side of the bottom surface **100b**, the inductor component **1** is a surface-mount-type electronic component that allows surface mounting with the bottom surface **100b** being a mount surface and that can reduce a mounting area.

In the inductor component **1**, the outer surfaces **100** further include a top surface **100t** that is positioned on a back side of the bottom surface **100b**, and the outer-surface conductors **11** include bottom-surface conductors **11b** that are disposed above the bottom surface **100b** and top-surface conductors **11t** that are disposed above the top surface **100t**. The bottom-surface conductors **11b** and the top-surface conductors **11t** are electrically connected to each other by the through wirings **13**. Further, in the inductor component **1**, a circularly extending wiring **110** that is formed from the bottom-surface conductors **11b**, the top-surface conductors **11t**, and the through wirings **13** circularly extends around a winding axis **AX** that is parallel to the bottom surface **100b**.

Due to the structure above, since the winding axis **AX** is parallel to the mount surface of the inductor component **1**, magnetic flux that is a main component of magnetic flux which is generated by the inductor element **L** and which passes the inside diameter of the circularly extending wiring **110** does not intersect a mounting board, so that it is possible to reduce reduction in a **Q** value of the inductor element **L** caused by an eddy current loss and to reduce noise emission with respect to the mounting board.

In the inductor component **1**, the single-layer glass plate **10** includes cavities **C**. Therefore, the effective dielectric constant is lower than that of a single-layer glass plate **10** that does not include cavities **C**, so that a stray capacitance that is generated between any of the outer-surface conductors **11**, any of the terminal electrodes **12**, any of the through wirings **13**, and a wiring pattern on the mounting board can be reduced, and, in particular, reduction in self-resonant frequency of the inductor element **L** can be suppressed from occurring.

By performing a processing method (described below), it is possible to form the cavities **C** in any shape and in any place in the single-layer glass plate **10**. For example, the inductor component **1** includes a cavity **C1** along a periphery of the terminal electrode **12**. In the inductor component **1**, the circularly extending wiring **110** circularly extends at least two times around the wiring axis **AX**, and the single-layer glass plate **10** includes a cavity **C2** between adjacent portions of the circularly extending wiring **110**. In the inductor component **1**, the single-layer glass plate **10** includes a cavity **C3** at a location including the winding axis **AX**.

In this way, at a location of the inductor component **1** where a potential difference is large and lines of electric force tend to be generated, when the cavities **C1** to **C3** are formed, it is possible to further effectively reduce stray capacitance. The inductor component **1** may include only one or two of the cavities **C1** to **C3**, or may not include the cavities **C1** to **C3**. The cavities **C1** to **C3** may or may not extend through the single-layer glass plate **10**, or may be formed at least near the wirings. For example, the cavities **C1** to **C3** do not extend through the single-layer glass plate **10**. The cavities **C1** to **C3** may be filled with a magnetic material such as a ferrite plate or a resin containing magnetic powder such as metal magnetic powder or ferrite powder.

Further, as shown in FIG. 5, in the inductor component **1**, the single-layer glass plate **10** includes a crystallization portion **101** (shown by hatching). Therefore, by using the crystallization portion **101**, it is possible to adjust the effective dielectric constant of the single-layer glass plate **10** and

to increase or decrease a stray capacitance that is generated between any of the outer-surface conductors **11**, any of the terminal electrodes **12**, any of the through wirings **13**, and the wiring pattern on the mounting board, in particular, to adjust the self-resonant frequency of the inductor element **L**.

In FIG. 5, although, in the inductor component **1**, the single-layer glass plate **10** includes the crystallization portion **101** at a location including the winding axis **AX**, the location of the crystallization portion **101** is not limited thereto. The locations of the cavities **C1** to **C3** and the location of the crystallization portion **101** may be transposed. The single-layer glass plate **10** may include only the cavities **C** or only the crystallization portion **101**, or may include neither of them. When, as in the inductor component **1**, the cavity **C3** and the crystallization portion **101** are both situated at locations including the winding axis **AX**, the depth of the cavity **C3** and the depth of the crystallization portion **101** may be the same or may differ, and the cavity **C1** and the crystallization portion **101** may be adjacent to each other or may be disposed apart from each other.

Next, the cross-sectional shape of the inductor component **1** is described. FIGS. 6 and 7 are each a schematic sectional view of the inductor component **1**. Specifically, the cross section of FIG. 6 is a cross section of a portion in enlarged form near the bottom surface **100b** on a side of the second terminal electrode **122** in a cross section including the winding axis **AX** and orthogonal to the bottom surface **100b**. The cross section of FIG. 7 is a cross section of a portion in enlarged form near the top surface **100t** in a cross section including the winding axis **AX** and orthogonal to the top surface **100t**.

As shown in FIGS. 6 and 7, in the inductor component **1**, the bottom surface **100b** and the top surface **100t**, which are the outer surfaces **100** of the single-layer glass plate **10**, each have grooved portions **G1** or grooved portions **G2** that are each recessed with respect to a vicinity; and the outer-surface conductors **11** include grooved-portion conductors **11g** that are each disposed in a corresponding one of the grooved portions **G1** and **G2**.

In the structure above, since the range of formation of the grooved-portion conductors **11g** is restricted by the grooved portions **G1** and **G2**, the grooved-portion conductors **11g** are formed with high precision. Therefore, in the inductor component **1**, further, the precision of the shape and characteristics of the inductor element **L** is increased. Since the terminal electrodes **12** more easily protrude than the grooved-portion conductors **11g** towards the side of the bottom surface **100b**, solder is unlikely to adhere to the grooved-portion conductors **11g** when mounting the inductor component **1** onto the mounting board, so that the mountability of the inductor component **1** is increased.

At this time, it is more desirable that portions of the single-layer glass plate **10** be disposed between adjacent grooved-portion conductors **11g**, so that the insulation property and the electrochemical migration resistance between the adjacent grooved-portion conductors **11g** with the portions of the single-layer glass plate **10** interposed therebetween are further increased. In this case, compared to the case in which the portions of the single-layer glass plate **10** are not interposed, it is possible to further reduce the interval between the grooved-portion conductors **11g**, and the efficiency with which the inductance value (**L** value) with respect to the external shape of the inductor component **1** is obtained is increased.

As shown in FIG. 6, on the side of the bottom surface **100b** of the inductor component **1**, thickness **11T** of each grooved-portion conductor **11g** is less than depth **G1T** of

each grooved portion G1. Therefore, since the grooved-portion conductors 11g do not protrude from the single-layer glass plate 10, the grooved-portion conductors 11g are unlikely to become damaged when, for example, manufacturing or mounting the inductor component 1.

As shown in FIG. 6, it is desirable that the inductor component 1 include a protective film 14 that covers the outer-surface conductors 11 (the grooved-portion conductors 11g). This makes it possible to suppress damage to the outer-surface conductors 11 from occurring. Further, in the inductor component 1, since the thickness 11T of each grooved-portion conductor 11g is less than the depth G1T of each grooved portion G1, the protective film 14 can be made thin. This means that, in the height dimension of the inductor component 1, the proportion that the protective film 14 occupies can be reduced. In this case, since the inside diameter of the circular shape of the circularly extending wiring 110 can be further increased, the efficiency with which the L value and the Q value per external shape of the inductor component 1 are obtained is increased.

The protective film 14 is not a required structure. The inductor component 1 may not include the protective film 14, or only a part of the inductor component 1 may include the protective film 14. For example, in particular, it is desirable that the protective film 14 cover the outer-surface conductors 11 and that the terminal electrodes 12 be exposed. Although similarly not required, by covering the single-layer glass plate 10 with the protective film 14, it is possible to reduce damage to the single-layer glass plate 10 from occurring.

As shown in FIG. 7, on a side of the top surface 100t of the inductor component 1, thickness 11T of each grooved-portion conductor 11g is greater than depth G2T of each grooved portion G2. Therefore, when the height dimension of the inductor component 1 has been prescribed, compared to outer-surface conductors 11 disposed on the top surface 100t instead of in the grooved portions G2, the thickness 11T of each grooved-portion conductor 11g can be increased and the direct current resistance of each grooved-portion conductor 11g can be reduced. Therefore, the efficiency with which the Q value per external shape of the inductor component 1 is obtained is increased. By increasing the thickness 11T, since the thermal capacity of each grooved-portion conductor 11g is also increased, the heat dissipation characteristics of the inductor element L are also improved.

Although, in the description above, the bottom surface 100b and the top surface 100t of the inductor component 1 include the corresponding grooved portions G1 and G2 having the corresponding depths G1T and G2T whose relationships with the corresponding thicknesses 11T of the grooved-portion conductors 11g differ from each other, the inductor component 1 is not limited to such a structure. For example, each grooved portion G1 may be formed in the top surface 100t, each grooved portion G2 may be formed on the side of the bottom surface 100b, only the grooved portions G1 or the grooved portions G2 may be formed in one or both of the bottom surface 100b and the top surface 100t.

The grooved portions G1 and G2 are not required structures of the inductor component 1. FIG. 8 is a schematic sectional view of the inductor component 1 and shows a cross section corresponding to the cross section of FIG. 6. As shown in FIG. 8, the outer-surface conductors 11 need not include grooved-portion conductors 11g. A structure including grooved portions G1 for circular extensions of respective outer-surface conductors 11, a structure including grooved

portions G2 for circular extensions of respective outer-surface conductors 11, or a structure not including grooved portions may be provided.

As shown in FIG. 6, the inductor component 1 further includes anchor sections 123 that protrude into the single-layer glass plate 10 from the second terminal electrode 122. Although not shown, a side of the first terminal electrode 121 also has a similar structure. Therefore, the fixing strength of the terminal electrodes 12 with respect to the single-layer glass plate 10 is increased. In FIG. 6, although the anchor sections 123 protrude up to an intermediate position of the single-layer glass plate 10 from the bottom surface 100b, the anchor sections 123 may protrude up to the top surface 100t and extend through the single-layer glass plate 10.

Although the anchor sections 123 are formed in holes formed in the single-layer glass plate 10, it is desirable that the anchor sections 123 fill the entire holes to further increase the fixing strength of the terminal electrodes 12 with respect to the single-layer glass plate 10.

The anchor sections 123 are not required structures of the inductor component 1. Anchor sections 123 need not be provided, or anchor sections 123 may be provided at only one of the side of the first terminal electrode 121 and the side 25 of the second terminal electrode 122. Further, in FIG. 6, although two anchor sections 123 protrude from the second terminal electrode 122, the number of anchor sections 123 is not limited thereto, and may be one or three or more.

As illustrated in the drawings, for explanatory convenience, hereunder, a direction that is a longitudinal direction of the single-layer glass plate 10 and that goes toward the second terminal electrode 122 from the first terminal electrode 121 is defined as an x direction. Of directions that are orthogonal to the x direction, the direction that goes toward the top surface 100t from the bottom surface 100b is defined as a z direction, and the direction that is orthogonal to the x direction and the z direction and that defines a right hand system when x, y, and z are arranged in this order is defined as a y direction. When, for example, orientations are not 35 considered, directions that are parallel to the respective x, y, and z directions may be indicated as respective L direction, W direction, and T direction.

Due to the definitions above, above the bottom surface 100b, which is an outer surface 100, refers to a direction that 45 goes opposite to the z direction from the bottom surface 100b; and above the top surface 100t, which is an outer surface 100, refers to a direction that goes towards the z direction from the top surface 100t. The thickness of each outer-surface conductor 11, which includes, for example, each grooved-portion conductor 11g, is a thickness in a direction that is orthogonal to the outer surface 100 that is positioned below the outer-surface conductors 11. For example, in FIGS. 6 and 7, the thickness of each grooved-portion conductor 11g is a thickness of each conductor in the 55 T direction.

2. Structure of Each Portion Single-Layer Glass Plate 10

The single-layer glass plate 10 functions as an insulator and a structural body of the inductor component 1. From the 60 viewpoint of manufacturing methods (described below), it is desirable that the single-layer glass plate 10 be made of a photosensitive glass plate, a typical example thereof being Foturan II (registered trademark of Schott AG). In particular, it is desirable that the single-layer glass plate 10 contain cerium oxide (ceria: CeO_2), in which case the cerium oxide 65 becomes a sensitizing agent, and processing by photolithography is further facilitated.

However, the single-layer glass plate 10 can be processed by, for example, machining, such as drilling or sandblasting; dry/wet etching using, for example, a photoresist/metal mask; or laser processing. Therefore, a glass plate that is not photosensitive may be used. The single-layer glass plate 10 may be one in which glass paste has been sintered, or may be formed by a publicly known method, such as a float method.

The single-layer glass plate 10 is a single-layer plate member in which wirings, such as internal conductors integrated with the inside of a glass body, are not placed in the glass body. In particular, the single-layer glass plate 10 includes the outer surfaces 100 as the boundaries between the outer side portion and the inner side portion of the glass body. Since the through holes V, the grooved portions G1, and the grooved portions G2, formed in the single-layer glass plate 10, are also boundaries between the outer side portion and the inner side portion of the glass body, they are defined as the outer surfaces 100.

Although the single-layer glass plate 10 is basically in an amorphous state, the single-layer glass plate 10 may include the crystallization portion 101. For example, when Foturan II above is used, although the dielectric constant of amorphous glass is 6.4, the dielectric constant can be reduced to 5.8 by crystallization. Therefore, it is possible to reduce the parasitic capacitance between conductors near the crystallization portion 101.

Outer-Surface Conductors 11

The outer-surface conductors 11 are wirings disposed above the corresponding one of the outer surfaces 100 of the single-layer glass plate 10, that is, on the outer side portion of the single-layer glass plate 10, and constitute at least part of the inductor element L, which is an electrical element. More specifically, the outer-surface conductors 11 include the bottom-surface conductors 11b that are disposed on the bottom surface 100b of the single-layer glass plate 10 and the top-surface conductors 11t that are disposed on the top surface 100t of the single-layer glass plate 10. Each bottom-surface conductor 11b has a shape extending in the W direction and each top-surface conductor 11t extends in the W direction while being slightly tilted in the L direction. Therefore, the circularly extending wiring 110 has a substantially helical shape in which a change-over to a next spiral occurs at each top-surface conductor 11t.

The outer-surface conductors 11 are made of conductive materials having high conductivity, such as copper, silver, gold, or an alloy thereof. The outer-surface conductors 11 may be metal films formed by, for example, plating, evaporation, or sputtering, or may be a metal sintered body in which a conductor paste has been applied and sintered. The outer-surface conductors 11 may have a multi-layer structure including a plurality of metal layers that are stacked upon each other, or may be one in which, for example, when a protective film 14 is not included, a film made of nickel, tin, gold, or the like is formed at an outermost layer. It is desirable that the thickness of the outer-surface conductors 11 be 5 μm or more and 50 μm or less (i.e., from 5 μm to 50 μm).

It is desirable that the outer-surface conductors 11 be formed by a semi-additive method. This makes it possible to form the outer-surface conductors 11 having low electrical resistance, high precision, and high aspect. For example, the outer-surface conductors 11 can be formed as follows. First, a titanium layer and a copper layer are formed in this order by performing a sputtering method or electroless plating on the entire outer surfaces 100 of each single-layer glass plate 10 after division into individual pieces to form a seed layer,

and a patterned photoresist is formed on the seed layer. Next, a copper layer is formed by electroplating on the seed layer at a cavity portion of the photoresist. Thereafter, the photoresist and the seed layer are removed by wet etching or dry etching. Therefore, the outer-surface conductors 11 that have been patterned to any shape can be formed on the outer surfaces 100 of each single-layer glass plate 10.

Terminal Electrodes 12

The terminal electrodes 12 are terminals of the inductor element L and are disposed above the outer surface 100 of the single-layer glass plates 10 and are electrically connected to the outer-surface conductors 11. As shown in FIG. 5, the terminal electrodes 12 are exposed to the outside of the inductor component 1. More specifically, the terminal electrodes 12 include the first terminal electrode 121 and the second terminal electrode 122 that are disposed on the bottom surface 100b of the single-layer glass plate 10, and the first terminal electrode 121 and the second terminal electrode 122 are exposed to the outside only at the bottom surface 100b.

However, the terminal electrodes 12 are not limited to the structure above. The number of terminal electrodes 12 may be three or more, and the terminal electrodes 12 may also be formed on a side surface adjacent to the bottom surface 100b, or on the top surface 100t. The terminal electrodes 12 can be formed by using any of the materials and manufacturing methods exemplified for the outer-surface conductors 11.

For example, as shown in FIG. 6, by forming the terminal electrodes 12 on the outer surface 100 of the single-layer glass plate 10 at locations above the outer-surface conductors 11, the terminal electrodes 12 may protrude above the outer-surface conductors 11. For example, as shown in FIG. 7, the terminal electrodes 12 may protrude above the outer-surface conductors 11 by making the terminal electrodes 12 thicker than the outer-surface conductors 11. When the outer-surface conductors 11 are covered with the protective film 14, the terminal electrodes 12 need not protrude from the protective film 14. A principal surface of each terminal electrode 12 may be positioned closer than the protective film 14 to a side of the single-layer glass plate 10. In this case, mountability may be increased by forming a solder ball on the principal surface of each terminal electrode 12.

Although the inductor component 1 includes the anchor sections 123 that protrude into the single-layer glass plate 10 from the terminal electrodes 12, the anchor sections 123 may be formed by, for example, a method in which, prior to forming the terminal electrodes 12, non-through holes or through holes are formed by performing a processing method (described later) on the single-layer glass plate 10, and conductors are formed in the non-through holes or the through holes by using any of the materials and manufacturing methods exemplified for the outer-surface conductors 11. For example, a seed layer may be formed in the non-through holes or the through holes and in a terminal electrode formation region in the vicinity thereof to form conductors that are caused to fill the non-through holes or the through holes by performing electroplating. The terminal electrodes 12 and the anchor sections 123 may be separately formed, or may be formed using the same seed layer to integrally form the terminal electrodes 12 and the anchor sections 123, so that the terminal electrodes 12 are those subjected to high anchoring effect.

Through Wirings 13

The through wirings 13 are wirings that extend through the corresponding through holes V formed in the single-layer glass plate 10 and that are electrically connected to the

corresponding outer-surface conductors **11**, and constitute at least part of the inductor element **L**. In particular, the circularly extending wiring **110** including the outer-surface conductors **11** and the through wirings **13** has a substantially helical shape circularly extending around the winding axis **AX** and constitutes the main portion of the inductor element **L**. By performing a method (described below), the through wirings **13** can be formed in the through holes **V** previously formed in the single-layer glass plate **10** by using any of the materials and manufacturing methods exemplified for the outer-surface conductors **11**.

In FIGS. 3 and 5, although the through wirings **13** are formed in the through holes **V** formed in a direction orthogonal to the bottom surface **100b** and the top surface **100t**, it is not limited thereto. For example, in each single-layer glass plate **10** after the division into individual pieces, the through holes **V** may be formed in a direction parallel to the bottom surface **100b** and the top surface **100t** to form wirings that extend in the direction parallel to the bottom surface **100b** and the top surface **100t**.

Protective Film **14**

The protective film **14** is a member that has the role of preventing damage to the outer-surface conductors **11** from occurring by protecting the outer-surface conductors **11** from external forces, and the role of increasing the insulation property of the outer-surface conductors **11**. It is desirable that the protective film **14** be, for example, an inorganic film made of an oxide, a nitride, or an oxynitride of, for example, silicon or hafnium, having excellent insulation property and capable of easily being made thin. However, the protective film **14** may be a resin film made of, for example, epoxy or polyimide that allows easier formation thereof.

As shown in FIG. 7, the protective film **14** may cover the single-layer glass plate **10** and the outer-surface conductors **11** (the grooved-portion conductors **11g**) on the top surface **100t**. This makes it possible to form a pickup surface of a mounting device when mounting the inductor component **1** onto the mounting board.

3. Processing Method of Single-Layer Glass Plate **10**

In the inductor component **1**, prior to forming the inductor element **L** including, for example, the outer-surface conductors **11**, the terminal electrodes **12**, and the through wirings **13**, the single-layer glass plate **10** is a processing body including previously formed through holes **V**, previously formed cavities **C**, a previously formed crystallization portion **101**, previously formed grooved portions **G1** and **G2**, etc. In processing the single-layer glass plate **10**, although it is possible to use publicly known methods including the above-described methods, it is most desirable to perform the processing using photosensitive glass, thereby allowing the processing to be performed with high precision. The processing method using photosensitive glass is described below.

(1) Preparation of Board

First, a photosensitive glass board, which is an assembly of portions that become the single-layer glass plates **10**, is prepared. For the photosensitive glass board, for example, Foturan II can be used. In general, the photosensitive glass board contains an oxide of silicon, lithium, aluminum, cerium, or the like to allow photolithography with high precision.

(2) Exposure

Next, portions of the prepared photosensitive glass board where, for example, the through holes **V**, the cavities **C**, the crystallization portion **101**, and the grooved portions **G1** and **G2** are to be formed are irradiated with, for example, ultraviolet light having a wavelength of approximately 310

nm. The irradiation with ultraviolet light causes, for example, metal ions, such as cerium ions, in the photosensitive glass to be oxidized by light energy to discharge electrons. Here, the final processing depth of the single-layer glass plates **10** can be controlled by adjusting the irradiation amount of ultraviolet light in accordance with the thickness of the photosensitive glass board. For example, by setting the irradiation amount to a large amount, it is possible to form the through holes **V** that extend up to the top surface **100t** from the bottom surface **100b** of each single-layer glass plate **10**, whereas, by adjusting the irradiation amount to a small amount, it is possible to form the non-through holes, such as the cavities **C** and the grooved portions **G1** and **G2**.

As an exposure device used in irradiating the photosensitive glass board with ultraviolet light, a contact aligner or a stepper that allows ultraviolet light having a wavelength of approximately 310 nm to be obtained can be used. Alternatively, a laser irradiation device including a femtosecond laser can be used as a light source. When a femtosecond laser is used, by condensing laser light in an internal portion of the photosensitive glass board, it is possible to discharge electrons from metal oxide only at a light-condensing portion. That is, it is possible to photosensitize only the internal portion without photosensitizing a surface of a laser-light irradiation portion of the photosensitive glass board.

Therefore, each single-layer glass plate **10** is designed with greater freedom. For example, as with the locations where the cavity **C3** and the crystallization portion **101** of the inductor component **1** are formed, inner portions that are not exposed at the bottom surface **100b** and the top surface **100t**, which are surfaces where the outer-surface conductors **11** are formed, that is, portions of the photosensitive glass board other than the exposed surfaces can be processed.

(3) Firing

The photosensitive glass board after the exposure above is fired. Specifically, the photosensitive glass board is fired at temperatures in two stages, for example, first, at a temperature near 500°C. Therefore, in the ultraviolet-light irradiation portion of the photosensitive glass board, ions, such as silver ions, gold ions, or copper ions, are reduced by discharged electrons to form a nano-cluster of metal atoms. Next, the photosensitive glass board is fired at a temperature near 560°C. Therefore, the nano-cluster of metal atoms becomes a crystalline nucleus and a crystal phase of, for example, lithium metasilicate is deposited in the vicinity of the crystalline nucleus. The crystal phase of, for example, lithium metasilicate easily dissolves in hydrofluoric acid, and this characteristic is used in the next etching step.

In uniformly depositing the crystal phase above in a plane of the photosensitive glass board, the temperature distribution inside a firing furnace needs to be uniform and is desirably within $\pm 3^\circ$ C.

(4) Etching

After the firing, the etching step using a hydrofluoric acid aqueous solution is performed. It is desirable that the concentration of hydrofluoric acid aqueous solution be, for example, 5 to 10%. In the etching step, the entire photosensitive glass board after the firing above is immersed in the hydrofluoric acid aqueous solution. Therefore, only the crystal phase inside the board is etched and the through holes or the non-through holes are formed. For the purpose of smoothening the surface of the etched photosensitive glass board, the hydrofluoric acid aqueous solution may contain an acid other than hydrofluoric acid, such as hydrochloric acid or nitric acid.

When the crystallization portion **101** is to be formed in each single-layer glass plate **10**, for example, a portion of the

crystal phase that becomes the crystallization portion **101** may be covered with a barrier layer that is resistant to a hydrofluoric acid aqueous solution to prevent the hydrofluoric acid aqueous solution from being immersed in the crystal phase. After the step above, if necessary, the thickness of the photosensitive glass board may be adjusted by grinding the photosensitive glass board.

(5) Formation of Conductors

For example, the outer-surface conductors **11**, the terminal electrodes **12**, and the through wirings **13** are formed at the corresponding outer surfaces of the photosensitive glass board after the etching step above by, for example, a semi-additive method. The outer-surface conductors **11**, the terminal electrodes **12**, and the through wirings **13** may be formed from a single seed layer, or may be formed by separate steps. When the thickness of the outer-surface conductors **11** and the thickness of the terminal electrodes **12** are to be different, for example, while covering the outer-surface conductors **11** with the protective film **14**, only portions that become the terminal electrodes **12** may be further subjected to electroplating, or a seed layer may be formed again to form a multi-layered conductor layer.

After forming the conductors, if necessary, the conductors are coated with or laminated with a resin to form the protective film **14**, and the photosensitive glass board is divided into individual pieces by, for example, using a dicing blade, so that an inductor component **1** including the single-layer glass plates **10** is completed.

In the manufacturing method above, since after sintering each single-layer glass plate **10** of the inductor component **1**, the conductors, such as the outer-surface conductors **11**, the terminal electrodes **12**, and the through wirings **13** are formed, it is possible to reduce the influence caused by the firing.

In the above, although, in the etching step, the crystallization portion **101** is formed by covering a portion of the crystal phase with a barrier layer that is resistant to a hydrofluoric acid aqueous solution, it is not limited thereto. For example, it is possible to, by irradiating with ultraviolet light again the photosensitive glass board after the formation of conductors or the inductor component **1** after the division into pieces, slightly crystallize the irradiation portion and form the crystallization portion **101**. This causes the crystallization portion **101** to be formed with greater freedom.

4. Modifications

Although, as the first reference example, the inductor component **1** has been described, the inductor component **1** may have additional structures below that have not been described above.

Low Transmittance Portion **102**

FIGS. 9, 10, and 11 are each a schematic top view of the inductor component **1**. The inductor component **1** includes a low transmittance portion **102** (shown by hatching) on at least a part of an outer surface **100** of the single-layer glass plate **10**, the low transmittance portion **102** having a light transmittance that is lower than that of the vicinity thereof. Therefore, the single-layer glass plate **10** having high light transmittance and low visibility has improved visibility and is easy to handle when manufacturing and using the inductor component **1**. The low transmittance portion **102** has a light transmittance that is lower than that of the vicinity thereof with regard to at least some of the wavelengths, and has low light transmittance with regard to, for example, a wavelength of infrared light, visible light, or ultraviolet light, or a plurality of such wavelengths.

The low transmittance portion **102** can be formed, for example, by using a photosensitive glass for the single-layer

glass plate **10** and, similarly to the crystallization portion **101** above, partly crystallizing the single-layer glass plate **10**. The transmittance of the low light-transmission portion **102** can be controlled as appropriate on the basis of, for example, the irradiation amount/irradiation time of ultraviolet light or heating.

As shown in FIG. 9, it is desirable that the low transmittance portion **102** be positioned on an outer peripheral edge of one surface of the outer surfaces **100** of the single-layer glass plate **10**, such as of the top surface **100t** in FIG. 9. This makes it possible to, regarding the one surface, easily perceive the outer peripheral edge, in particular, more easily examine the outer appearance at the time of manufacture or use.

As shown in FIG. 10, it is desirable that the low transmittance portion **102** have a cross-shape on one surface of the outer surfaces **100** of the single-layer glass plate **10**, for example, on the top surface **100t** in FIG. 10. This makes it possible to, regarding the one surface, use the cross shape as an alignment mark in, for example, photolithography and to increase processing precision. The cross shape can also be used as a directional mark indicating the polarities of the inductor component **1**.

As shown in FIG. 11, the low transmittance portion **102** may be formed on one entire surface of the outer surfaces **100** of the single-layer glass plate **10**, for example, on the entire top surface **100t** in FIG. 11. This makes it possible to, by not allowing the bottom-surface conductors **11b** and the terminal electrodes **12** to be perceived from the opposite side, for example, from the bottom surface **100b**, increase the precision with which anything is perceived from the top surface **100t**. Here, it is possible to, by causing the amorphous portion of the single-layer glass plate **10** to partly remain, such as at the cross shape, provide an alignment mark or a directional mark, as that shown in FIG. 10.

Underlying Insulation Layer **15**

FIG. 12 is a schematic sectional view of the inductor component **1** and shows locations corresponding to those shown in FIG. 6. As shown in FIG. 12, the inductor component **1** may further include an underlying insulation layer **15** disposed on an outer surface **100** of the single-layer glass plate **10**, or the bottom surface **100b** in FIG. 12, and the terminal electrodes **12** may be disposed on the underlying insulation layer **15**. At this time, the outer-surface conductors **11** may also be disposed on the underlying insulation layer **15**. In this way, the outer-surface conductors **11** and the terminal electrodes **12** may be disposed not only directly on the outer surface **100** of the single-layer glass plate **10**, but also above the outer surface **100** with a different member (the underlying insulation layer **15**) interposed therebetween.

By using the underlying insulation layer **15**, it is possible to adjust, for example, the heights of formation and the degree of close contact of the outer-surface conductors **11** and the terminal electrodes **12**, and the electrical characteristics of the inductor element **L**.

The underlying insulation layer **15** can be formed by, for example, in the above-described manufacturing method, laminating the photosensitive glass board before forming a seed layer with a resin film, such as ABF GX-92 (manufactured by Ajinomoto Fine-Techno Co., Inc.), or applying, subjecting to thermosetting, etc. a paste-like resin with respect to the photosensitive glass board before forming a seed layer.

The underlying insulation layer **15** may be disposed on the outer-surface conductors **11**. FIG. 4 is a schematic perspective view of an inductor component **1a** according to

the modification as viewed from a bottom surface. FIG. 13 is a schematic sectional view of the inductor component 1a. FIG. 13 shows locations corresponding to those shown in FIG. 6.

In the inductor component 1a, bottom-surface conductors 11b extend in an L direction on the bottom surface 100b, which is an outer surface 100 of the single-layer glass plate 10, the underlying insulation layer 15 is disposed on the bottom-surface conductors 11b, and the terminal electrodes 12 are disposed on the underlying insulation layer 15. In this way, by forming the outer-surface conductors 11 and the terminal electrodes 12 in different layers, it is possible to design a layout of the outer-surface conductors 11 and the terminal electrodes 12 with greater freedom. In particular, as in the inductor component 1a, by forming the outer-surface conductors 11 in a longitudinal direction of the single-layer glass plate 10, the inside diameter of the circularly extending wiring is increased, so that the efficiency with which the L value and the Q value of the inductor element L with respect to the external shape of the inductor component 1a are obtained is increased.

By forming through wirings (not shown) formed in the underlying insulation layer 15, the terminal electrodes 12 can be electrically connected to the bottom-surface conductors 11b and the through wirings 13. Instead of disposing only the terminal electrodes 12 on the underlying insulation layer 15, as a re-wiring layer, a wiring that is electrically connected to the bottom-surface conductors 11b and the through wirings 13 may be disposed at the underlying insulation layer 15. This allows the inductor element L to be designed with greater freedom.

FIG. 14 is a schematic side view of the inductor component 1. FIG. 14 is a figure showing the inductor component 1 as viewed from a side surface 100s parallel to the L direction and the T direction in a plane in which the bottom surface 100b and the top surface 100t are connected. FIG. 14 does not show the circularly extending wiring 110.

As shown in FIG. 14, in the inductor component 1, the single-layer glass plate 10 includes a reinforcing portion 103 that is harder than the vicinity thereof. An electronic component, such as the inductor component 1, tends to be damaged due to an external force or a thermal shock applied to the inductor component 1 during a manufacturing process or after mounting. In particular, at interfaces between elements having different physical properties, that is, between the single-layer glass plate 10, the outer-surface conductors 11, the terminal electrodes 12, and the through wirings 13, stress tends to concentrate and cracks tend to be produced in the single-layer glass plate 10 with the interfaces as starting points. In the structure above, since the strength can be properly reinforced by the reinforcing portion 103 against local damage and cracks, the strength of the inductor component 1 is increased.

The reinforcing portion 103 can be formed, for example, by using a photosensitive glass for the single-layer glass plate 10 and, similarly to the crystallization portion 101 above, by partly crystallizing the single-layer glass plate 10. The transmittance of the reinforcing portion 103 can be controlled as appropriate on the basis of, for example, the irradiation amount/irradiation time of ultraviolet light or heating.

In particular, it is desirable that the reinforcing portion 103 be positioned below the outer-surface conductors 11 or below the terminal electrodes 12. This makes it possible to effectively reduce the local damage and cracks above. Further, it is desirable that the reinforcing portion 103 be

positioned below an outer peripheral edge of each outer-surface conductor 11 or an outer peripheral edge of each terminal electrode 12.

The manufacturing method of the inductor component 1 can also be changed as appropriate. For example, in the manufacturing method described above, individual pieces of single-layer glass plates may be formed by cutting the photosensitive glass board by a photolithography method, the photosensitive glass board having the outer-surface conductors formed thereon.

According to the manufacturing method above, it is possible to cut the photosensitive glass board with high precision while reducing chipping when dividing the photosensitive glass board into pieces. Since this method does not cause a physical shock to be applied to the photosensitive glass board when cutting with a dicing machine as when a dicing blade is used, it is possible to suppress micro-cracks from being produced in the single-layer glass plates. Further, compared to when a dicing blade is used, it is possible to reduce a cutting margin when dividing the photosensitive glass board into pieces, and to increase the number of single-layer glass plates that can be obtained from a photosensitive glass board of the same size.

SECOND REFERENCE EXAMPLE

Although, in the first reference example, the outer-surface conductors are part of the inductor element, the outer-surface conductors are not limited thereto and thus may be part of an electrical element other than the inductor element L. FIG. 15 is a schematic sectional view of a capacitor component 2 according to a second reference example. As shown in FIG. 15, the capacitor component 2 is a surface-mount-type electronic component that includes, as an electrical element, a capacitor element Cap widely used in an electronic circuit.

The capacitor component 2 includes the single-layer glass plate 10 above, outer-surface conductors 21 that are part of the capacitor element Cap serving as an electrical element, and terminal electrodes 22 that are terminals of the capacitor element Cap. The outer-surface conductors 21 are disposed above outer surfaces 100 of the single-layer glass plate 10. The terminal electrodes 22 are disposed above an outer surface 100 and are electrically connected to the outer-surface conductors 21.

Due to the structure above, in the capacitor component 2, since the outer-surface conductors 21 and the terminal electrodes 22 are disposed above the corresponding outer surfaces 100 of the single-layer glass plate 10, the outer-surface conductors 21 and the terminal electrodes 22 are not placed in the single-layer glass plate 10. Therefore, the capacitor component 2 makes it possible to reduce the influence of firing.

In the capacitor component 2, the outer surfaces 100 of the single-layer glass 10 include a bottom surface 100b that is one principal surface of the single-layer glass plate 10 and a top surface 100t that is positioned on the back side of the bottom surface 100b, and the outer-surface conductors 21 include a substantially planar bottom-surface flat-plate electrode 21b, where the outer-surface conductor 21 is disposed above the bottom surface 100b (in an opposite z direction in FIG. 15) and a substantially planar top-surface flat-plate electrode 21t that is disposed above the top surface 100t (in the z direction in FIG. 15).

Due to the structure above, in the capacitor component 2, the capacitor element Cap is formed by causing the bottom-surface flat-plate electrode 21b and the top-surface flat-plate

electrode 21_t to be opposite to each other with the single-layer glass plate 10, which is a dielectric layer, interposed therebetween.

In the capacitor component 2, the single-layer glass plate 10 has a cavity C21 at a location interposed between the bottom-surface flat-plate electrode 21_b and the top-surface flat-plate electrode 21_t. The cavity C21 may be the crystallization portion 101 shown in FIG. 5. The capacitor component 2 may include a highly dielectric portion that has a dielectric constant higher than that of the single-layer glass plate 10 and that is disposed in the cavity C21.

Due to the structure above, in the capacitor component 2, it is possible to adjust the capacitance value of the capacitor element Cap by using the cavity C21, the crystallization portion 101, or the highly dielectric portion. Specifically, the dielectric constant of the cavity C21 and the dielectric constant of the crystallization portion 101 are lower than the dielectric constant of the single-layer glass plate 10, so that it is possible to reduce the overall dielectric constant of the dielectric layer on whose respective sides the bottom-surface flat-plate electrode 21_b and the top-surface flat-plate electrode 21_t are disposed. The highly dielectric portion has a dielectric constant that is higher than that of the single-layer glass plate 10, so that it is possible to increase the overall dielectric constant of the dielectric layer above.

In particular, according to a method of forming the cavity C21 and the crystallization portion 101 by using the photosensitive glass board above, it is possible to form the cavity C21 and the crystallization portion 101 after forming the capacitor element Cap including the bottom-surface flat-plate electrode 21_b and the top-surface flat-plate electrode 21_t and to adjust the electrical characteristics of the capacitor element Cap after measuring the electrical characteristics of the capacitor element Cap, so that it is possible to adjust the capacitance of the capacitor component 2 and to increase yield. The capacitor component 2 may include only one of the cavity C21, the crystallization portion 101, and the highly dielectric portion, or may include a combination of these.

The capacitor component 2 further includes through wirings 23 that are at least part of the capacitor element Cap, the through wirings 23 extending through through holes V formed in the single-layer glass plate 10 and being electrically connected to the outer-surface conductors 21.

Due to the structure above, in the capacitor component 2, it is possible to form a wiring in a vertical direction with respect to the outer-surface conductors 21 and the terminal electrodes 22, which are disposed above the corresponding outer surfaces 100, and the conductor element Cap is formed with greater freedom. In the capacitor component 2, the through wirings 23 are wirings that connect the top-surface flat-plate electrode 21_t and the terminal electrodes 22.

In the capacitor component 2, the terminal electrodes 22 include a first terminal electrode 221 and a second terminal electrode 222, which are input/output terminals of the capacitor element Cap, and the first terminal electrode 221 and the second terminal electrode 222 each have a shape including a principal surface that is parallel to the bottom surface 100_b at a location above the bottom surface 100_b (opposite z direction).

Due to the structure above, since the capacitor component 2 includes the input/output terminals of the capacitor element Cap, each having a surface that allows solder to adhere thereto in a direction parallel to the bottom surface 100_b, on a side of the bottom surface 100_b, the capacitor component 2 is a surface-mount-type electronic component that allows

surface mounting with the bottom surface 100_b being a mount surface, and that can reduce a mounting area.

The capacitor component 2 further includes a protective film 24 that covers a part of the bottom-surface flat-plate electrode 21_b. This makes it possible to prevent damage to the bottom-surface flat-plate electrode 21_b from occurring and to increase insulation property. In particular, by causing a part of the bottom-surface flat-plate electrode 21_b to be exposed from the protective film 24, it is possible to define this part as the terminal electrode 22 (the first terminal electrode 221).

THIRD REFERENCE EXAMPLE

15 Although, in the first reference example and the second reference example, the electronic component is an electronic component including one electrical element, the electronic component is not limited thereto, so that the electronic component may include a plurality of electrical elements 20 therein. FIG. 16 is an electrical circuit diagram of an electronic component 3 according to a third reference example. The electronic component 3 is a surface-mount-type electronic component that includes, as electrical elements, an inductor element L and capacitor elements Cap1 and Cap2.

25 As shown in FIG. 16, in the electronic component 3, a first terminal electrode 321 is a common terminal of the inductor element L and the capacitor element Cap1, a second terminal electrode 322 is a common terminal of the inductor element 30 L and the capacitor element Cap2, and a third terminal electrode 323 is a common terminal of the capacitor elements Cap1 and Cap2. Therefore, in the electronic component 3, the inductor element L and the capacitor elements Cap1 and Cap2 constitute a π -type LC filter.

35 Next, a specific structure of the electronic component 3 is described. FIG. 17 is a schematic top view of the electronic component 3. FIG. 18 is a schematic sectional view of the electronic component 3. FIG. 19 is a schematic bottom view of the electronic component 3. FIG. 18 is a sectional view 40 along an alternate long and short dashed line, that is, along XVI-XVI shown in FIG. 17.

45 The electronic component 3 includes a single-layer glass plate 10A, outer-surface conductors 31, and terminal electrodes 32 that are terminals of the inductor element L, the capacitor element Cap1, or the capacitor element Cap2. The outer-surface conductors 31 are each disposed above (opposite z direction) a bottom surface 100Ab or above (z direction) a top surface 100At, the bottom surface 100Ab and the top surface 100At being outer surfaces of the single-layer glass plate 10A, and are part of the inductor element L, the capacitor element Cap1, or the capacitor element Cap2. The terminal electrodes 32 are disposed above (opposite z direction) the bottom surface 100Ab and are electrically connected to the outer-surface conductors 31.

55 The outer-surface conductors 31 disposed above the top surface 100At are grooved-portion conductors 31ga, 31gb, and 31gc similarly to the grooved-portion conductors 11g shown in FIG. 6.

60 Due to the structure above, in the electronic component 3, since the outer-surface conductors 31 are each disposed on a corresponding one of the outer surfaces 100Ab and 100At of the single-layer glass plate 10A, the outer-surface conductors 31 are not placed in the single-layer glass plate 10A. Therefore, the electronic component 3 makes it possible to 65 reduce the influence of firing.

The electronic component 3 further includes a second single-layer glass plate 10B that differs from the single-layer

glass plate 10A. The second single-layer glass plate 10B is disposed above (z direction) the grooved-portion conductors 31ga, 31gb, and 31gc. Conversely, this means that the grooved-portion conductors 31ga, 31gb, and 31gc are disposed above (opposite z direction) the bottom surface 100Bb, which is an outer surface, with respect to the second single-layer glass plate 10B.

Due to the structure above, in the electronic component 3, the grooved-portion conductors 31ga, 31gb, and 31gc can be internal conductors, and three-dimensional wiring is possible by providing multi-layers, so that the electronic component 3 is designed with greater freedom. As described above, since the grooved-portion conductors 31ga, 31gb, and 31gc are disposed above the top surface 100At and the bottom surface 100Bb, which are outer surfaces, with respect to the single-layer glass plate 10A and the second single-layer glass plate 10B, the grooved-portion conductors 31ga, 31gb, and 31gc are not placed in the single-layer glass plate 10A and the second single-layer glass plate. Therefore, even in the structure above, the electronic component 3 makes it possible to reduce the influence of firing.

In the electronic component 3, the top surface 100At of the single-layer glass plate 10A and the bottom surface 100Bb of the second single-layer glass plate 10B are joined to each other. Therefore, the electronic component 3 can have a multi-layer structure. A method of joining the single-layer glass plate 10A and the second single-layer glass plate 10B when the grooved-portion conductors 31ga, 31gb, and 31gc have been formed after sintering the single-layer glass plate 10A and the second single-layer glass plate 10B is described below.

The electronic component 3 further includes outer-surface conductors 41 that are disposed above (z direction) a top surface 100Bt, which is an outer surface of the second single-layer glass plate 10B, and are part of the inductor element L. Due to the structure above, in the electronic component 3, since the outer-surface conductors 41 are disposed above an outer surface of the second single-layer glass plate 10B, the outer-surface conductors 41 are not placed in the second single-layer glass plate 10B. Therefore, the electronic component 3 makes it possible to reduce the influence of firing.

In the electronic component 3, the grooved-portion conductors 31ga, 31gb, and 31gc include substantially planar grooved-portion flat-plate electrodes 31ga and 31gc, and the outer-surface conductors 31 include substantially planar facing flat-plate electrodes 31b facing the grooved-portion flat-plate electrodes 31ga and 31gc with the single-layer glass plate 10A interposed therebetween.

Due to the structure above, in the electronic component 3, the grooved-portion flat-plate electrodes 31ga and 31gc and the corresponding facing flat-plate electrodes 31b constitute the corresponding capacitors Cap1 and Cap2. Specifically, the facing flat-plate electrodes 31b include facing flat-plate electrodes 31ba and 31bc facing the corresponding grooved-portion flat-plate electrodes 31ga and 31gc; the grooved-portion flat-plate electrode 31ga and the facing flat-plate electrode 31ba constitute the capacitor element Cap1; and the grooved-portion flat-plate electrode 31gc and the facing flat-plate electrode 31bc constitute the capacitor element Cap2. In this way, the electronic component 3 has the capacitor elements Cap1 and Cap2 built therein.

Further, in the electronic component 3, as shown in FIGS. 18 and 19, by the facing flat-plate electrodes 31b including a third terminal electrode 323 that is a portion exposed from the protective film 34, the terminal electrodes 32 are provided.

Due to the structure above, in the electronic component 3, it is possible to reduce the size and height of the electronic component 3 as an electronic component including an LC filter. In ordinary multi-layer-type electronic components, from the viewpoint of ensuring strength, an outer-layer portion between internal electrodes and the outer surfaces of such electronic components is made thicker than interlayer insulation layers disposed in the interior. Therefore, when the facing flat-plate electrodes are disposed on an outer surface of such electronic components, the electrode interval between the facing flat-plate electrodes and flat-plate electrodes inside a multi-layer body is increased, as a result of which the required electrical characteristics may not be obtained. Therefore, ordinarily, the facing flat-plate electrodes facing the flat-plate electrodes inside the multi-layer body are also disposed inside the multi-layer body. Therefore, in addition to the structure being a three-layer structure including the flat-plate electrodes, the facing flat-plate electrodes, and the terminal electrodes, the outer layer between the facing flat-plate electrodes and the terminal electrodes becomes thicker than the interlayer insulation layers between the flat-plate electrodes and the facing flat-plate electrodes, and the overall thickness is increased.

On the other hand, in the electronic component 3, since a sufficient strength of the single-layer glass plate 10A can be ensured, it is possible to thinly process the glass plate than before and to dispose the facing flat-plate electrodes 31b on the outer surface 100Ab. As a result, the electronic component 3 is a two-layer structure including the grooved-portion flat-plate electrodes 31ga and 31gc and the facing flat-plate electrodes 31b, and the single-layer glass plate 10A can be made sufficiently thin and compared to existing structures, the size and height of the electronic component 3 can be reduced. In particular, in the electronic component 3, since a side of the top surface 100At of the single-layer glass plate 10A is a side of the grooved-portion flat-plate electrodes 31ga and 31gc, it is possible to reduce the distance between the electrodes of each of the capacitor elements Cap1 and Cap2 while reducing the influence on the strength (the thickness) of the single-layer glass plate 10A.

In the electronic component 3, as described above, since the facing flat-plate electrodes 31b are used as the terminal electrodes 32, it is possible to reduce the number of electrodes for forming the capacitor elements Cap1 and Cap2, so that it is possible to reduce the stray capacitance, improve the electrical characteristics, and reduce variations in the characteristics.

The electronic component 3 further includes through wirings 33 and 43 that are at least part of the inductor element L, the capacitor element Cap1, or the capacitor element Cap2, the through wirings 33 and 43 extending through through holes V formed in a corresponding one of the single-layer glass plates 10A and 10B and being electrically connected to a corresponding one of the outer-surface conductors 31 and 41.

Due to the structure above, in the electronic component 3, it is possible to form a wiring in a vertical direction with respect to the outer-surface conductors 31 and 41 and the terminal electrodes 32, which are disposed above the corresponding outer surfaces 100, and the inductor element L, the capacitor element Cap1, or the capacitor element Cap2 is formed with greater freedom.

In the electronic component 3, the through wirings 33 are wirings that connect the corresponding grooved-portion flat-plate electrodes 31ga and 31gc to the corresponding first and second terminal electrodes 321 and 322. In the electronic component 3, the through wirings 43 connect the

31

grooved-portion conductors **31gb** and the corresponding outer-surface conductors **41** to each other, and a circularly extending wiring constituted by the grooved-portion conductors **31gb**, the outer-surface conductors **41**, and the through wirings **43** circularly extends around a winding axis (not shown) that is parallel to the bottom surface **100Ab**. Due to the structure above, the circularly extending wiring constitutes a main portion of the inductor element **L**, and becomes the electronic component **3** including the inductor element **L**.

In the electronic component **3**, the terminal electrodes **32** include the first terminal electrode **321**, the second terminal electrode **322**, and the third terminal electrode **323**, which are each an input/output terminal of any of the inductor element **L**, the capacitor element **Cap1**, and the capacitor element **Cap2**; and, at locations above (opposite z direction) the bottom surface **100Ab**, the first terminal electrode **321**, the second terminal electrode **322**, and the third terminal electrode **323** each have a shape including a principal surface that is parallel to the bottom surface **100Ab**.

Due to the structure above, since the electronic component **3** includes the input/output terminals of the inductor element **L**, the capacitor elements **Cap1**, or the capacitor element **Cap2**, each having a surface that allows solder to adhere thereto in a direction parallel to the bottom surface **100Ab**, on a side of the bottom surface **100Ab**, the electronic component **3** is a surface-mount-type electronic component that allows surface-mounting with the bottom surface **100Ab** being a mount surface and that can reduce a mounting area.

The electronic component **3** further includes the protective film **34** that covers part of the facing flat-plate electrodes **31b**, specifically, the facing flat-plate electrodes **31ba** and **31bc**. Therefore, it is possible to prevent damage to the facing flat-plate electrodes **31ba** and **31bc** from occurring and to increase insulation property. In particular, by causing a part of the facing flat-plate electrodes **31b** to be exposed from the protective film **34**, it is possible to define this part as the terminal electrode **32** (the third terminal electrode **323**).

Method of Joining Single-Layer Glass Plate **10A** and Second Single-Layer Glass Plate **10B**

In the electronic component **3**, the top surface **100At** of the single-layer glass plate **10A** and the bottom surface **100Bb** of the second single-layer glass plate **10B** are joined to each other. The glass plates may be directly joined to each other by, for example, using a photosensitive glass for the single-layer glass plate **10A** or the second single-layer glass plate **10B** and activating the surface of the photosensitive glass by wet etching or dry etching. The top surface **100At** of the single-layer glass plate **10A** and the bottom surface **100Bb** of the second single-layer glass plate **10B** may be joined to each other by interposing an adhesive layer, such as a thermosetting resin layer or a thermoplastic resin layer, between them.

At this time, for example, the grooved-portion conductors **31ga**, **31gb**, and **31gc** may be formed on the single-layer glass plate **10A** before the joining or may be formed after the single-layer glass plate **10A** and the second single-layer glass plate **10B** have been joined to each other. Specifically, for example, it is possible to, after forming grooved portions in the top surface **100At** of the single-layer glass plate **10A** and disposing the grooved-portion conductors **31ga**, **31gb**, and **31gc** in the grooved portions, join the top surface **100At** of the single-layer glass plate **10A** and the bottom surface **100Bb** of the second single-layer glass plate **10B** to each other.

32

The method is not limited thereto. For example, it is possible to form grooved portions in the top surface **100At** of the single-layer glass plate **10A** after joining the top surface **100At** to the second single-layer glass plate **10B** or 5 join the single-layer glass plate **10A** and the second single-layer glass plate **10B** to each other after forming grooved portions in the top surface **100At**, and then form the grooved-portion conductors **31ga**, **31gb**, and **31gc** in the grooved portions. When the grooved-portion conductors **31ga**, **31gb**, and **31gc** are formed in the grooved portions 10 after the joining of the plates, the grooved-portion conductors **31ga**, **31gb**, and **31gc** can be brought into close contact with the top surface **100At** of the single-layer glass plate **10A** and the bottom surface **100Bb** of the second single-layer glass plate **10B**, which is desirable. Even if an adhesive layer is used, spaces between the grooved-portion conductors **31ga**, **31gb**, and **31gc** and each of the top surface **100At** of the single-layer glass plate **10A** and the bottom surface **100Bb** of the second single-layer glass plate **10B** can be 15 filled due to plastic deformation of the adhesive layer, which is desirable.

In the electronic component **3**, although the grooved-portion flat-plate electrodes **31ga** and **31gc** and the facing flat-plate electrodes **31ba** and **31bc** face each other with the 20 single-layer glass plate **10A** interposed therebetween, the outer-surface conductors **41** may include the substantially planar facing flat-plate electrodes or the terminal electrodes that face with the second single-layer glass plate **10B** interposed therebetween.

In the electronic component **3**, the facing flat-plate electrodes **31b** may be grooved-portion flat-plate electrodes. At this time, the grooved-portion flat-plate electrodes are the terminal electrodes **32**.

In the electronic component **3**, although the circularly 25 extending wiring, which is a main portion of the inductor element **L**, circularly extends on a side of the second single-layer glass plate **10B**, the circularly extending wiring may circularly extend on a side of the single-layer glass plate **10A**.

FOURTH REFERENCE EXAMPLE

Although, in the first reference example to the third reference example, the electronic components are surface-mount-type electronic components, they are not limited thereto. For example, a three-dimensional mounting electronic component may be used. FIG. 20 is a schematic perspective view of an electronic component **4** according to 45 a fourth reference example. The electronic component **4** is a three-dimensional mounting sensor including a sensor element that detects whether or not there is a fluid **F** and a flow rate.

In the electronic component **4**, a top-surface flat-plate electrode **51t** and a bottom-surface flat-plate electrode **51b** 50 that are disposed above a top surface **100t** and a bottom surface **100b**, respectively, of a single-layer glass plate **10** are outer-surface conductors, which are part of the sensor element, and are terminal electrodes, which are terminals of the sensor element. That is, even the electronic component **4** includes the single-layer glass plate **10**, and the top-surface flat-plate electrode **51t** and the bottom-surface flat-plate electrode **51b**, which are disposed above the outer surface **100t** and the outer surface **100b** of the single-layer glass plate **10**, respectively, and which are part of the sensor element and which are terminals. Therefore, the electronic component **4** makes it possible to reduce the influence of 55 firing.

33

Since the electronic component 4 includes the terminal electrodes 51t and 51b at the respective top and bottom surfaces 100t and 100b, for example, if one of the terminal electrodes 51t and 51b is mounted on a land of a board, such as a substrate or an interposer, and the other of the terminal electrodes 51t and 51b is connected to a terminal of a semiconductor chip by using solder, a bonding wire, or the like, three-dimensional mounting becomes possible.

In the electronic component 4, the single-layer glass plate 10 includes principal surfaces, that is, the top surface 100t and the bottom surface 100b, and a side surface 100s that is orthogonal to the top surface 100t and the bottom surface 100b. The top-surface flat-plate electrode 51t and the bottom-surface flat-plate electrode 51b, which are outer-surface conductors, are disposed at the respective principal surfaces that are outer surfaces. The single-layer glass plate 10 includes a cavity C4 that opens in the side surface 100s.

Due to the structure above, an electronic element using the cavity C4 can be designed. Specifically, with the cavity C4 being defined as a flow path, the electronic component 4 is capable of detecting whether or not a fluid that flows in the cavity C4 exists or the flow rate of the fluid as changes in electrostatic capacity at the top-surface flat-plate electrode 51t and the bottom-surface flat-plate electrode 51b, and can be used as a fluid sensor. However, the method of use of the cavity C4 is not limited thereto. For example, it is possible to, by using the cavity C4 as a through hole in which a through wiring is disposed, design a more sophisticated electrical element. For example, if the through wiring is connected to a ground electrode of a mounting board via the side surface 100s, it is possible to, when a surge voltage caused by static electricity or a lightning strike occurs, form a path into which a surge current is caused to flow to a side of the ground electrode and provide the electronic component 4 with the function of dealing with static electricity.

OTHER REFERENCE EXAMPLES

The various features that have been described in the first reference example, the second reference example, the third reference example, and the fourth reference example above can be individually added, deleted, and changed in relation to each of the reference examples or in relation to other reference examples. Further, publicly known structures can be added to, deleted from, and changed in relation to these reference examples.

The electronic components according to the first to fourth reference examples above or according to reference examples in which any of the first to fourth reference examples has been modified as appropriate are desirably mounted on a particular mounting board. FIG. 21 is a schematic sectional view of an electronic-component mounting board 5.

The electronic-component mounting board 5 includes the inductor component 1 of the first reference example, the capacitor component 2 of the second reference example, and a glass board 10C on which the inductor component 1 and the capacitor component 2 of the second reference example are mounted.

According to the structure above, since the single-layer glass plate 10, which is a structural body of the inductor component 1 and the capacitor component 2, and the glass board 10C are made of the same material and their coefficients of linear expansion are close to each other, the inductor component 1 and the capacitor component 2 can be made more reliable with respect to thermal expansion and

34

thermal shrinkage occurring in the glass board 10C in, for example, a thermal shock test.

As described above, what is mounted on the glass board 10C is an electronic component using a single-layer glass plate as a structural body, and may be, for example, the electronic component 3 or the electronic component 4. Electronic components other than these electronic components may also be mounted. Even in this case, at least electronic components using a single-layer glass plate as a structural body can be made more reliable.

The glass board 10C may be one corresponding to a printed wiring board used in an electronic device, an auxiliary board that is mounted on the printed wiring board, such as a mother board, or a built-in board, such as an interposer or a substrate, used in a semiconductor or an electronic module.

While preferred reference examples of the disclosure have been described above, it is to be understood that variations and modifications will be apparent to those skilled in the art without departing from the scope and spirit of the disclosure. The scope of the disclosure, therefore, is to be determined solely by the following claims.

What is claimed is:

1. An inductor component comprising:
a single-layer glass plate of a rectangular parallelepiped shape with a length, a width, and a height, the length being longer than the width, the single-layer glass plate having a bottom surface defined by the length and the width and a top surface positioned on a back side of the bottom surface;
bottom-surface conductors disposed on the bottom surface and top-surface conductors disposed on the top surface;
through wirings each extending through a corresponding one of through holes in the single-layer glass plate;
an underlying insulation layer disposed above the bottom-surface conductors; and
a first terminal electrode and a second terminal electrode disposed above the underlying insulation layer, the bottom-surface conductors, the top-surface conductors, and the through wirings being electrically connected to each other to constitute a circularly extending wiring that circularly extends around a winding axis parallel to the bottom surface and the length,
the circularly extending wiring, the first terminal electrode, and the second terminal electrode being electrically connected to each other to constitute an inductor element,
the single-layer glass plate containing cerium oxide, and
the single-layer glass plate including a grooved portion on the bottom surface, wherein the bottom-surface conductors are wound around the bottom surface along the grooved portion.
2. The inductor component of claim 1, wherein
the first terminal electrode and the second terminal electrode are each shaped to have, above the bottom surface, a principal surface parallel to the bottom surface.
3. The inductor component of claim 1, wherein
the first terminal electrode and the second terminal electrode are positioned overlapping with the bottom-surface conductors, as viewed from a direction parallel to the height.

35

4. The inductor component of claim 1, wherein the circularly extending wiring circulates one or more times at a position overlapping with the first terminal electrode, as viewed from a direction parallel to the height.
5. The inductor component of claim 1, wherein the circularly extending wiring does not circulate three or more times at a position overlapping with the first terminal electrode, as viewed from a direction parallel to the height.
6. The inductor component of claim 1, wherein the underlying insulation layer covers whole of the bottom surface.
7. The inductor component of claim 1, wherein the underlying insulation layer covers all of the bottom-surface conductors.
8. An inductor component comprising:
a single-layer glass plate of a rectangular parallelepiped shape with a length, a width, and a height, the length being longer than the width, the single-layer glass plate having a bottom surface defined by the length and the width and a top surface positioned on a back side of the bottom surface;
bottom-surface conductors disposed on the bottom surface and top-surface conductors disposed on the top surface;
through wirings each extending through a corresponding one of through holes in the single-layer glass plate; an underlying insulation layer disposed above the bottom-surface conductors; and
a first terminal electrode and a second terminal electrode disposed above the underlying insulation layer, the bottom-surface conductors, the top-surface conductors, and the through wirings being electrically connected to each other to constitute a circularly extending wiring that circularly extends around a winding axis parallel to the bottom surface and the length, the circularly extending wiring, the first terminal electrode, and the second terminal electrode being electrically connected to each other to constitute an inductor element,
the underlying insulation layer being an inorganic film, and
the single-layer glass plate including a grooved portion on the bottom surface, wherein the bottom-surface conductors are wound around the bottom surface along the grooved portion.
9. The inductor component of claim 8, wherein the first terminal electrode and the second terminal electrode are each shaped to have, above the bottom surface, a principal surface parallel to the bottom surface.
10. The inductor component of claim 8, wherein the first terminal electrode and the second terminal electrode are positioned overlapping with the bottom-surface conductors, as viewed from a direction parallel to the height.

36

11. The inductor component of claim 8, wherein the circularly extending wiring circulates one or more times at a position overlapping with the first terminal electrode, as viewed from a direction parallel to the height.
12. The inductor component of claim 8, wherein the circularly extending wiring does not circulate three or more times at a position overlapping with the first terminal electrode, as viewed from a direction parallel to the height.
13. The inductor component of claim 8, wherein the underlying insulation layer covers whole of the bottom surface.
14. The inductor component of claim 8, wherein the underlying insulation layer covers all of the bottom-surface conductors.
15. An inductor component comprising:
a single-layer glass plate of a rectangular parallelepiped shape with a length, a width, and a height, the length being longer than the width, the single-layer glass plate having a bottom surface defined by the length and the width and a top surface positioned on a back side of the bottom surface;
bottom-surface conductors disposed on the bottom surface and top-surface conductors disposed on the top surface;
through wirings each extending through a corresponding one of through holes in the single-layer glass plate; an underlying insulation layer disposed above the bottom-surface conductors; and
a first terminal electrode and a second terminal electrode disposed above the underlying insulation layer, the bottom-surface conductors, the top-surface conductors, and the through wirings being electrically connected to each other to constitute a circularly extending wiring that circularly extends around a winding axis parallel to the bottom surface and the length, and the circularly extending wiring, the first terminal electrode, and the second terminal electrode being electrically connected to each other to constitute an inductor element, wherein
the underlying insulation layer covers a part of the bottom surface and does not cover any area that connects to the sides of the bottom surface.
16. The inductor component of claim 15, wherein the first terminal electrode and the second terminal electrode are each shaped to have, above the bottom surface, a principal surface parallel to the bottom surface.
17. The inductor component of claim 15, wherein the first terminal electrode and the second terminal electrode are positioned overlapping with the bottom-surface conductors, as viewed from a direction parallel to the height.
18. The inductor component of claim 15, wherein the circularly extending wiring circulates one or more times at a position overlapping with the first terminal electrode, as viewed from a direction parallel to the height.
